Primary Examiner — Terry Wallace(57) **CLAIM**

The ornamental design for a combined bite-sized hot dog and sausage preparer, as shown and described.

DESCRIPTION

FIG. 1 is a perspective view of a bite-sized hot dog and sausage preparer showing my new design.

FIG. 2 is a left side view thereof.

FIG. 3 is a right side view thereof.

FIG. 4 is a rear view thereof.

FIG. 5 is a front view thereof.

FIG. 6 is a top plan view thereof.

FIG. 7 is a bottom plan view thereof.

FIG. 8 is an exploded perspective view thereof in an open position and the corers separated from the preparer.

FIG. 9 is a right side view of FIG. 8.

FIG. 10 is a left side view of FIG. 8.

FIG. 11 is a top plan view of FIG. 8; and,

FIG. 12 is a bottom plan view of FIG. 8.
